(57) **CLAIM**

The ornamental design for a tablet case, as shown and described.

DESCRIPTION

FIG. 1 is a front, top perspective view of a tablet case, showing my new design;
FIG. 2 is a rear, bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;

FIG. 9 is an enlarged perspective view of detail “9” identified in FIG. 1;
FIG. 10 is an enlarged perspective view of detail “10” identified in FIG. 1;
FIG. 11 is an enlarged perspective view of detail “11” identified in FIG. 2;
FIG. 12 is an enlarged perspective view of detail “12” identified in FIG. 2; and,
FIG. 13 is another perspective view thereof, shown in an alternative position.

The dashed lines in the figures illustrate portions of the tablet case that form no part of the claimed design. The dash dot dash lines in FIGS. 1, 2, 9, 10, 11 and 12 are for the purpose of illustrating the enlarged views indicators and form no part of the claimed design.
